PORTABLE ELECTRIC LANTERN

Robert E. Brindley, New York, and David O. Chase,
Camillus, N.Y., and William W. Sammons, Pittsfield,
Mass., assignors to Union Carbide Corporation, a cor-
poration of New York

Filed Mar. 1, 1968, Ser. No. 10,801

Term of patent 14 years

Int. Cl. D26—04

U.S. Cl. D48—24

FIG. I.

FIG.2.

FIG.4.

FIG.3.

FIG.5.

FIGURE 1 is a perspective view showing the top, front and one side of a portable electric lantern embodying our design;

FIGURE 2 is an elevational view showing the front side of the lantern;

FIGURE 3 is a plan view showing the top of the lantern;

FIGURE 4 is an elevational view showing the back side of the lantern; and

FIGURE 5 is a plan view showing the bottom of the lantern.

We claim:

The ornamental design for a portable electric lantern, as shown.
